UNITED STATES PATENT OFFICE

171,056

PAIR OF EYEGLASSES OR SIMILAR ARTICLE

Elsa Schiaparelli, Paris, France

Application October 28, 1952, Serial No. 22,013

Claims priority, application France May 7, 1952

Term of patent 14 years

(Cl. D57—1)

To all whom it may concern:

Be it known that I, Elsa Schiaparelli, a citizen of France, residing at Paris, France, have invented a new, original, and ornamental Design for Pair of Eyeglasses, or Similar Article, of which the following is a specification, reference being had to the accompanying drawings, forming a part thereof.

In the drawings:

Fig. 1 is a perspective view of a pair of eyeglasses, showing my new design, and

Fig. 2 is a perspective view thereof, showing the eyeglasses in folded position.

I claim:

The ornamental design for a pair of eyeglasses or similar article, as shown.

ELSA SCHIAPARELLI.
